UNITED STATES PATENT OFFICE.

CHARLES A. JUENGST, OF CROTON FALLS, NEW YORK.

SIGNATURE-GATHERING MACHINE.

1,071,555.

Specification of Letters Patent.

Patented Aug. 26, 1913.

Application filed January 18, 1909. Serial No. 472,777.

To all whom it may concern:

Be it known that I, CHARLES A. JUENGST, a citizen of the United States, and resident of Croton Falls, in the county of West-
5 chester and State of New York, have invented certain new and useful Improvements in Signature-Gathering Machines, of which the following is a specification.

My invention relates to improvements in 10 signature gathering machines and has reference particularly to the mechanism for detecting signatures of improper thickness which may be handled by the machine, and for detecting certain irregularities in the 15 working of the machine, as when a signature is missed in feeding, or more than one signature is taken.

The objects of my invention are to improve the detector mechanism and to increase the efficiency of the machine as a 20 whole.

In the carrying out of my invention I employ grippers or other sheet delivery devices for conveying the signatures or sheets between the hoppers and the carrier of the machine, together with means for actuating the grippers to cause them to normally deposit the signatures or sheets upon the carrier; and in connection with these parts I 25 employ detector mechanism capacitated when the signature or sheet is of improper thickness, or when a signature is missed by any of the delivery devices, when a signature is misplaced or too many signatures 30 are taken to affect the actuating means in such way as to cause the sheet delivery devices to deliver the sheets or signatures to a point other than upon the carrier. Thus in the normal operation of the machine, signatures are delivered from the successive 35 hoppers or boxes to the carrier in piles, in the ordinary manner of a machine of this character, and if any of the signatures handled by such devices are of improper thickness then the signatures are not delivered upon the carrier but are deposited to a 40 point other than the carrier. In addition to the above, means are provided for interrupting the operation of the carrier when imperfect signatures are detected or when 45 signatures are missed, so that the action of the carrier will properly accord with that of the sheet delivery devices. Also means are 50 preferably employed for automatically re-

storing all the parts to their normal operation so that the machine will be entirely automatic in its action.

In the preferred form of my invention I use grippers as the sheet delivery devices and I provide means for reciprocating or swinging these grippers between the signature hoppers and a point in rear of the carrier. I associate with the grippers, detector mechanism of some sort, preferably of the form shown in my Patent No. 761,496. Means for opening the grippers are provided which are normally capacitated to open the grippers at the proper point in the swing of the grippers to deposit the signatures upon the carrier. The specific form of these gripper opening means would preferably be a pair of cams, and connections between the said cams and the gripper, the cams being capacitated to cause the gripper jaws to open at different points, according to which cam is operative. The operativeness of the respective cams is determined by, and under control of the detector mechanism.

Instead of having the grippers reciprocate normally between the hoppers and a point to one side of the carrier the grippers may be caused to normally reciprocate between the hoppers and the carrier, and to reciprocate between the hoppers and a point to one side of the carrier only when a signature is missed or the signatures are of improper thickness. As a means for accomplishing this result I prefer to employ a crank and an adjustable pitman connection between said crank, and a rocker arm on the gripper supporting shaft, together with means for changing the connections between the several parts, so as to give to the gripper arms either a short or a long throw, dependent upon the proper working conditions of the machine. Specifically, the means just described would preferably consist of a rocker arm on the gripper-bearing shaft, carrying two wrist pins or bolts, and cam mechanism controlled by the detector means to bring either of the said pins into engagement with the pitman connections from the driving crank. These pins on the rocker arm would be relatively spaced so that according as to which of the said pins is in engagement with the pitman, the gripper shaft would be given a comparatively

slight or greater oscillation, so as to give to the gripper either a short or a long throw. In either type of the invention, therefore, the signatures are normally deposited upon 5 the carrier and if there is any irregularity due to any variation from the normal thickness, as when in the operation of the machine too many signatures are taken, or any of the signatures are missed, the whole line 10 of signatures is deposited to one side of the carrier. This depositing point for the defective signatures is preferably located to the rear of the carrier but if found desirable by making slight changes in the mechanism they could be deposited at a point intermediate between the hoppers and the carrier.

Another feature of the invention consists of stripper mechanism associated with the 20 carrier, acting normally to position the signatures properly upon the carrier, together with connections from the detector mechanism for rendering the said strippers inoperative when any imperfect signatures are 25 detected or when signatures are missed. Preferably I employ a rockshaft for actuating the strippers, which rockshaft is directly connected with the detector mechanism. Also I find it convenient to operate 30 the interrupting means for the carrier from the said rockshaft, as by means of a connection from the rockshaft for uncoupling a driving clutch for the carrier.

In the drawings are illustrated the preferred forms of the invention but it will be understood that various changes and modifications may be made in the construction and arrangement of the parts without departing from the spirit and scope of the invention.

In the drawings: Figure 1 is a view partly in elevation and partly in section through a signature gathering machine showing one of the grippers in position to 45 seize a signature. This view is taken substantially on the line 1-1 of Fig. 5. Fig. 2 is a similar view showing the position of the parts after a defective signature has been taken by the gripper. Fig. 3 is a broken 50 detail view of the adjustable gate member through which the detector finger is adapted to pass. Fig. 4 is a plan view of the double-throw cam together with its associated parts. Fig. 5 is a broken rear elevation taken at one end of the machine. Fig. 6 is a view partly in section and partly in elevation of a modified form of the invention. Fig. 7 is a broken plan view of the upper portion of the form of the invention shown 55 in Fig. 6. Fig. 8 is a sectional view taken on the line 8-8 of Fig. 7, the pitman 69 having reached a point higher than that shown in Fig. 6.

Similar reference characters denote like 65 parts throughout the several views.

I will first describe that form of the invention in which the sheet delivery devices move between the hoppers and a point to one side of the carrier, the sheet delivery devices being normally capacitated to deliver 70 the signatures to the carrier, and acting under abnormal conditions to deliver the signatures to a point at one side of the carrier.

In the several views wherein is illustrated the preferred construction of this first type 75 of the invention, the signature hoppers are indicated at 1, and the traveling carrier or conveyer upon which the signatures are deposited in piles in the usual manner, is designated 2. The signature or sheet delivery 80 devices are here shown as grippers 3, having relatively fixed and pivoted gripper jaws 4 and 5 respectively, for seizing and conveying the signatures, but of course it will be understood that other forms of sheet delivery devices may be employed. These grippers are carried by a rockshaft 6, and motion is communicated to the said rockshaft preferably by means of a crank 7, on the main driving shaft 8, a pitman connection 9, and a rocker arm 10, fast on the gripper shaft. The gripper shaft is thus given an oscillatory movement and the grippers are swung between the signature hoppers and a point 11, in rear of the carrier. 95

As a means for opening and closing the gripper jaws, I prefer to employ a rockshaft 12, a rocker arm 13, a pivoted lever 14, and link connections 15 and 16, between the lever 14 and the rocker arm, and the lever 14 100 and the pivoted gripper jaw. Motion is communicated to the rockshaft 12, preferably by means of one of the two cams 17 or 18, (see particularly Figs. 1, 3 and 5) a friction roller 19, carried by the bell crank 105 20, and engaging either of the cams, and a connecting rod 21, between the bell crank and an arm 22, on the rockshaft 12. These two cams are preferably mounted side by side on the main driving shaft and are fixed 110 with respect to said shaft, one of the cams being of lesser extent circumferentially (17, Fig. 1) than the other, thereby constituting short-throw and long-throw cams respectively. 115

The detector mechanism used in connection with the grippers preferably consists of the signal arms 23, which are pivoted upon the gripper shaft or elsewhere, and have the dependent extensions 24, provided 120 with a gate 25, through which the detector finger 26, on the detector arm 27, is adapted to pass under normal conditions. This detector arm is preferably carried by the pivoted member 14, so that the position of the detector finger is dependent upon the closed 125 relation of the gripper jaws. The extension 24 or the "gate member" as it might properly be called, is preferably pivoted to the hub portion of the signal arm at a point 28, 130

so that it may yield upward if accidentally struck by the detector arm, during its upward movement. The gate member of the detector mechanism is preferably adjustable, as by means of a pair of superposed plates 29, which are adjustably secured with relation to each other by means of the bolts 30. The link connection 16 is also preferably adjustable and this adjustment may readily be accomplished by means of the telescoping parts as shown, which are adapted to be adjusted longitudinally with respect to each other by means of an adjusting nut 31.

Connection is made between the detector mechanism and the gripper actuating parts, so that under normal conditions the grippers will be actuated to deposit the signatures upon the carrier, and under abnormal conditions the grippers will be actuated to deposit the signatures at a point other than the carrier. These connections preferably take the form of a trip shaft 32, carrying the arms 33, adapted to be engaged by the cam surface 34, of the signal arms, a rocker arm 35, on the trip shaft, a connecting rod 36, between the said rocker arm and an arm 37, on the stub shaft 38, which stub shaft is carried in bearings 39, on the bell cranks, the said shaft having an arm 40, provided with a pin 41, engaging the friction roll 19, and serving to shift the roll from one cam to the other. A spring 42, holds the friction roll in proper engagement with the cams. The two cams are of different "throw" or extent, the one cam 17, having a comparatively short throw and adapted to cause the grippers to open at a point to deliver the signature to the carrier, and the other cam 18, having a comparatively long throw to cause the gripper to open at a point in rear of the carrier.

In Fig. 1 the different parts are shown in their normal relation, and the gripper jaws are shown as having just seized a signature. The friction roll of the bell crank is in engagement with the short-throw cam, so that if no signatures are missed and if all the signatures are of the proper thickness, the cam and connections will cause the gripper jaws to open at a point over the carrier, and the signatures will be properly deposited upon the carrier. The grippers will continue their swing, however, to the end of their stroke, that is, to a point in rear of the carrier. Supposing, however, that a signature is missed by one of the grippers or too many signatures are taken by any of the grippers or if any of the signatures are of improper thickness, then the detector finger will be displaced to a greater or less extent and instead of passing through the gate, as it does under normal conditions, the detector finger will fail to register with the gate, and will engage one of the members or sides of the gate. As the gripper recedes,

therefore, the detector finger by reason of its engagement with the gate member, will swing the signal arm upward, causing the cam surface on the signal arm to engage the rocker arm 33, and rock the trip shaft 32. This motion of the trip shaft by reason of its connection with the stub shaft 38, imparts an oscillatory motion to the said stub shaft and causes the friction roll to be shifted from the short to the long-throw cam. The long-throw cam holds the gripper jaws closed until the grippers reach the end or approximately the end of their rearward stroke. Instead of being deposited upon the carrier, the defective batch of signatures are thus deposited at a point to one side of the carrier. For convenience of handling in operation, I prefer to deposit the defective signatures at a point in rear of the carrier but it will of course be understood that by minor changes in the relation of the parts, the defective signatures might be deposited at a point other than in rear of the carrier.

Associated with the carrier are the strippers 43, which serve to guide the signatures to the carrier. To prevent the strippers from interfering, when the signatures are to be deposited at one side of the carrier, means are provided for rendering the strippers inoperative when the signatures are to be thus deposited to one side of the carrier. In the preferred form these means consist of a rockshaft 44, having rocker arms 45 and 46, the inner set of rocker arms 46, being connected by the links 47, with the rocker arms 48, on the trip shaft 32. The strippers are movably mounted so as to be capable of being withdrawn from out of the path of the grippers. This may be done by slidingly securing the strippers to the guard 49, by means of the screws 50, which pass through the slots 51, in the strippers. Thus when the trip shaft is actuated due to the detection of a faulty signature or any other abnormal condition in the machine, the rockshaft 44, will be partially rotated and the strippers will be withdrawn out of the path of the grippers.

The carrier which receives the gathered signatures may be of any suitable construction but is here shown in the shape of a sprocket chain having a number of properly spaced division pins 52, which form the compartments for the various book sections. This carrier may be operated by any suitable means, such as a sprocket 53, on a stub shaft 54, having the bevel gear 55, on its one end. A driving pinion 56, on the driving shaft engages with the gear 55. The carrier travels at a rate proportionate to the operation of the grippers so that as the carrier advances, the signatures are successively deposited thereon in regular piles. When a signature of improper thickness is detected or when any other abnormal condition which

the machine is capable of detecting exists; it is desirable to interrupt the action of the carrier so that when the parts are restored to normal operation, the action of the carrier will be in correspondence with that of the grippers. For this reason, therefore, means are provided for interrupting the action of the carrier during such abnormal condition of the machine. This interrupting mechanism preferably takes the form of a clutch and connections for opening the clutch to stop the carrier. The driving and driven clutch members are indicated at 57 and 58, and a shifting fork 59, on the bell 10 crank 60, engages the movable clutch member for disengaging the same from the relatively fixed clutch member. The other end of the bell crank may conveniently be connected by a link 62, to a rocker arm 63, on 15 the rockshaft 44, so that whenever the rock-shaft is actuated due to conditions which have been described, the clutch will be disengaged and the operation of the carrier will be interrupted.

20 In some cases it might be desirable to stop the machine each time a defective signature is detected or when such other abnormal conditions exist which the machine detects and in such a case means would be 25 provided for stopping the operation of the entire machine, such as means for disengaging a clutch or for shifting a driving belt from a fast to a loose pulley. Means of this sort have been disclosed in my Patent No. 30 761,496. For the purposes of the present invention, however, I prefer to use means for automatically restoring all the parts to their normal operation just as soon as the abnormal conditions which have been detected 35 have been effaced or overcome. Such restoring means might and preferably would take the form of a tripping member 64, mounted fast on the gripper shaft and adapted when the gripper shaft oscillates on 40 the next forward stroke of the grippers, to engage the signal arm and throw the same backward to its original inactive position. Under the influence of the spring 65, the trip shaft is then restored to its first position 45 and through the connections before described, the cam for opening the grippers at the proper normal time is rendered operative, the strippers are rendered operative, and the clutch is engaged to cause the carrier to resume its normal operation.

50 The same principle of operation is involved in the modified form of the invention shown in Fig. 6 only in the latter case the grippers have a normal swing between the signature hoppers and the carrier, and only 55 under abnormal conditions do the grippers swing to a point one side of the carrier. The means for carrying out this latter result consist preferably of a cam member 66, 60 carried by the trip shaft 32, and adapted

when the trip shaft is positioned by the signal arm to extend the pin or bolt 67, so as to be engaged by the hook-like extension or end 68, on the pitman 69. This pitman is connected with the crank 7, on the main driving shaft. This pitman is forked or bifurcated and is provided with the forked ends 69 and 70, which ends are spaced from each other so that according as to which of the pitman forks is in engagement with the 70 crank arm 10, of the gripper shaft, the gripper shaft is given either a slight or a relatively great oscillation. The outer fork 70, of the pitman, is the one which is normally in driving engagement with the 75 crank arm. The connection with the crank arm is preferably made by means of a stud or bolt 71, on the crank arm engaging in a slot 72, in the outer pitman fork. The inner pitman fork, as before referred to, is 80 of hook-like formation so as to engage with the bolt 67, when the same is extended. This bolt 67, is normally withdrawn out of the path of the hook part 68, of the pitman, by means of the spring 73. In this 85 case, also, the jaws are preferably opened at the proper time by means of the cam 17-18 and related parts as before described, or similar means may be employed for this purpose. For the sake of clearness 90 the jaw operating means and the carrier have not been illustrated in this view. These parts have already been described and are particularly well illustrated in Figs. 1 and 5. In the normal operation of this 95 latter form of the machine the outer fork of the pitman is in active connection with the outer end of the crank arm and the said crank arm is oscillated to swing the gripper between the hopper and the carrier. If 100 now the detector parts be tripped due, say to the presence of a signature of improper thickness, the trip shaft will be oscillated and the cam member on said trip shaft will engage with the bolt 67, and cause the said 105 bolt to be projected into the path of the inner extension or fork of the pitman. The leverage of the pitman now instead of being exerted on the outer end of the crank arm will be exerted at an intermediate 110 point of the crank arm. This change in 115 leverage will impart a greater oscillation to the gripper shaft and the grippers will be oscillated to a point in rear of the carrier. At the same time, or approximately 120 so, the strippers will be withdrawn out of the way of the grippers, the carrier will be stopped and the devices for opening the gripper jaws will be actuated to open the 125 jaws at a point in rear of the carrier, the operation of these parts having been described already. As soon as abnormal conditions are overcome, the restoring means will act to cause the parts to resume their normal operation. A spring 74, is utilized 130

- to allow of a yielding action in the connection between the outer end of the crank arm and the pitman when the crank arm is subjected to the long-throw motion. The change in the swing of the grippers is preferably accomplished by means of shifting from a short-throw to a long-throw connection in the manner described, but if the defective signatures were to be deposited at the front side of the carrier the change in the connection would be from a long-throw to a short-throw, and other means might be employed for giving these different movements to the grippers.
15. What is claimed, is:
1. The combination in a signature gathering or like machine, of delivery mechanism arranged to take hold of the signatures or other articles being handled and having a movement to transport the articles so taken, means actuating the delivery mechanism to cause said delivery mechanism to normally deposit the articles being carried thereby at a definite point, and means exercising a control over the actuating means to cause said actuating means to actuate the delivery mechanism to deposit the articles at a point different from the normal point of deposit.
  2. The combination with a gripper of a signature-gathering or like machine, of means for actuating the gripper to cause it to seize and convey the signatures or other articles, and means for affecting the actuating means to cause the gripper to deposit the signatures at different points.
  3. In a signature gathering or like machine, the combination of delivery mechanism arranged to take hold of the signatures or other articles being handled and having a movement to transport the articles so taken, means actuating the delivery mechanism to cause said delivery mechanism to normally deposit the articles conveyed thereby at a definite point, and automatic means controlling the actuating means whereby to cause said actuating means to automatically actuate the delivery mechanism to deposit the articles at a point different from the normal point of deposit.
  4. In a signature gathering machine, the combination of signature hoppers, a receiver for the gathered products from the several hoppers, delivery mechanisms arranged to grip the signatures and having a movement to transport the signatures so gripped from the hoppers to the receiver, means actuating the delivery mechanisms to normally cause said delivery mechanisms to deposit the signatures carried thereby on the receiver, and means exercising a control over the actuating means to cause said actuating means to operate the delivery mechanisms to deposit the signatures at a point other than on the receiver.
5. In a signature gathering machine, the combination of signature hoppers, a carrier arranged to receive the gathered products from the several hoppers, delivery mechanisms arranged to grip the signatures in the hoppers and having a movement to transport the signatures so gripped from the hoppers to the carrier, means actuating the delivery mechanisms to normally cause said mechanisms to deposit the signatures upon the carrier, and means exercising a control over the actuating means whereby to cause said actuating means to actuate the delivery mechanisms to deposit the signatures at a point other than on the carrier.
6. The combination in a signature gathering or like machine, of a plurality of grippers for conveying the signatures or other articles, means for actuating the grippers to cause them to seize and convey the signatures or other articles, and means for affecting the actuating means to cause the grippers to deposit the signatures at different points.
7. In a signature gathering machine, signature hoppers, a carrier, grippers, actuating means normally causing the grippers to deliver the signatures from the hoppers to the carrier, and means acting under abnormal conditions to cause the grippers to deliver the signatures to another point than the carrier.
8. In a signature gathering machine, the combination with signature hoppers and a carrier, of means acting normally to take the signatures from the hoppers and deposit the signatures on the carrier, and under certain conditions to convey the signatures from the hoppers to another point than the carrier, and connections whereby the operation of the carrier will be interrupted when the signatures are not delivered to the carrier.
9. In a signature gathering machine, signature hoppers, a carrier, grippers, actuating means normally causing the grippers to deliver the signatures from the hoppers to the carrier, means acting under abnormal conditions to cause the grippers to deliver the signatures to another point than the carrier, and means acting automatically to cause the grippers to resume their normal operation.
10. In a signature gathering machine, signature hoppers, a carrier, grippers, actuating means normally causing the grippers to deliver the signatures from the hoppers to the carrier, means acting under abnormal conditions to cause the grippers to deliver the signatures to another point than the carrier and to interrupt the operation of the carrier, and means operating automatically to restore the parts to their normal operation.
11. In a signature gathering machine, signature hoppers, a carrier, grippers, means

actuating the grippers to cause them to normally deliver the signatures from the hopper to the carrier, and means acting under certain conditions to cause the grippers to deliver the signatures to one side of the carrier.

12. In a signature gathering machine, signature hoppers, a carrier, strippers coöperating with the carrier, grippers, means normally actuating the grippers to cause them to deliver signatures from the hoppers to the carrier, means acting under abnormal conditions to cause the grippers to deliver the signatures to one side of the carrier, and connections for rendering the strippers inoperative during the abnormal operation of the machine.

13. In a signature gathering machine, signature hoppers, a carrier, strippers coöperating with the carrier, grippers, means normally actuating the grippers to cause them to deliver signatures from the hoppers to the carrier, means acting under abnormal conditions to cause the grippers to deliver the signatures to one side of the carrier, connections for rendering the strippers inoperative during the abnormal operation of the machine, and connections for interrupting the action of the carrier during such abnormal operation.

14. In a signature gathering machine, signature hoppers, a carrier, strippers coöperating with the carrier, grippers, means normally actuating the grippers to cause them to deliver signatures from the hoppers to the carrier, means acting under abnormal conditions to cause the grippers to deliver the signatures to one side of the carrier, connections for rendering the strippers inoperative during the abnormal operation of the machine, and connections for interrupting the action of the carrier during such abnormal operating, and means for automatically restoring the parts to their normal operation.

15. In a signature gathering machine, signature hoppers, a carrier, traveling grippers for delivering the signatures from the hoppers to the carrier, means for actuating the grippers, detector mechanism for detecting any variation in the thickness of the signatures handled by the machine, said detector mechanism controlling the actuating means to cause the grippers to deliver the signatures to another point than the carrier when the signatures are of improper thickness.

16. The combination with the traveling grippers of a signature gathering machine, of detector mechanism associated therewith for detecting variations in the thickness of the signatures handled by the machine, and means for actuating the grippers, said actuating means being controlled by the detector mechanism to cause the grippers to deposit the signatures at different points.

17. In a signature gathering machine, the

combination with signature delivering means and actuating means for the same, of detector mechanism for detecting variations in the thickness of the signatures handled by the machine and capable of adjustment to signatures of different thickness, the actuating means being under control of the detector mechanism and capacitated accordingly to cause the delivery means to deposit the signatures at different points.

18. In a signature gathering machine, signature hoppers, a carrier, grippers, means for reciprocating the grippers between the signature hoppers and the carrier, means for actuating the grippers to cause them to seize the signatures and deliver them from the hoppers to the carrier, and means for affecting the actuating means to cause the grippers to carry the signatures beyond the carrier and deposit such signatures at a point beyond the carrier.

19. In a signature gathering machine, the combination with the traveling grippers of the machine and a carrier, of detector mechanism, means affected by said detector mechanism to cause the grippers to deposit the signatures upon the carrier or at another point, and means acting automatically to cause the grippers to resume their normal operation of depositing the signatures upon the carrier.

20. In a signature gathering machine, the combination with the signature hopper and carrier of the machine, of a traveling gripper, means for swinging the gripper with respect to the hopper and carrier, and means for causing the gripper to release the signature carried thereby at different points in the swing of the gripper so as to deposit the said signature either upon the carrier or elsewhere.

21. In a signature gathering machine, the combination with the traveling grippers of the machine, the hoppers and the carrier, of detector mechanism associated with the grippers, means for actuating the grippers, and connections between the detector mechanism and actuating means whereby when the signature handled by the gripper is of improper thickness the actuating means will be affected to deposit the signature at another point than the carrier.

22. In a signature gathering machine, the combination with the signature hoppers, carrier, and traveling grippers of the machine, of means for actuating the grippers to normally cause the grippers to deposit the signatures upon the carrier, and detector mechanism adapted when the signature handled by the gripper is of improper thickness to cause the gripper to open at a point to one side of the carrier to thereby deposit the imperfect signature to one side of the carrier.

23. In a signature gathering machine the

combination with the signature hoppers, carrier, and traveling grippers of the machine, of means for actuating the grippers to normally cause the grippers to deposit the signatures upon the carrier, detector mechanism adapted when the signature handled by the gripper is of improper thickness to cause the gripper to open at a point to one side of the carrier to thereby deposit the imperfect signature to one side of the carrier, and means associated with the detector mechanism acting to interrupt the operation of the carrier when a signature of improper thickness is detected.

24. In a signature gathering machine, signature hoppers, a carrier, grippers, actuating means for opening and closing the grippers and for swinging the grippers between the signature hoppers and the carrier, and between the signature-hoppers and a point to one side of the carrier, and means acting under certain conditions to cause the grippers to open in the position to one side of the carrier so as to deposit the signature to one side of the carrier.

25. In a signature gathering machine, signature hoppers, a carrier, grippers, means for swinging the grippers between the signature hoppers and a point in rear of the carrier, means acting normally to cause the grippers to open while in the position over the carrier, and means acting under abnormal conditions to cause the grippers to open while in position in rear of the carrier so as to deposit the signatures in rear of the carrier.

26. In a signature gathering machine, the combination with the grippers thereof and the means for opening and closing the same, of means for swinging the grippers, and means for causing the grippers to open at different points in the swing thereof.

27. In a signature gathering machine, the combination with the signature hoppers, a carrier, strippers associated with the carrier, of grippers, detector mechanism associated with the gripper, means for swinging the grippers between the hoppers and the carrier, and between the signature hoppers and a point to one side of the carrier, actuating means serving normally to cause the grippers to open in time to deposit the signatures on the carrier and under abnormal conditions to cause the grippers to deposit the signatures to one side of the carrier, means for rendering the strippers inoperative when the signatures are deposited to one side of the carrier, means for interrupting the operation of the carrier when the signatures are thus deposited to one side of the same, and means for automatically restoring all the parts to their normal operation.

28. The combination in a signature gathering machine, with the grippers and the

means for swinging the same, of detector mechanism associated with the grippers, cam mechanisms for opening the grippers at different points in the swing thereof and connections from the detector mechanism for controlling the relative operativeness of the different cam mechanisms.

29. In a signature gathering machine, the combination with the grippers, of means for actuating the grippers in a normal path, and means adapted to influence the said actuating means to give to the grippers a movement different from the normal movement of said grippers.

30. The combination in a signature gathering machine, of the signature hoppers and the carrier, of means for normally actuating the grippers to swing the grippers between the signature hoppers and the carrier, and means acting under certain conditions adapted to cause the grippers to move between the signature hoppers and a point to one side of the carrier.

31. The combination in a signature gathering machine, of the signature hoppers and a carrier, grippers, and detector mechanism associated therewith, means actuating the grippers to normally cause the grippers to deliver signatures from the hoppers to the carrier, and means controlled by the detector mechanism when a signature is of improper thickness to cause the grippers to deposit the imperfect signatures in rear of the carrier.

32. In a signature gathering machine, the combination with a traveling gripper and actuating means for the gripper, of a detector arm, movable with the gripper, and positioned in accordance with the thickness of material taken by the gripper, a signal arm, and a gate member having an opening therein for the normal passage of the detector arm, said gate member having a hinged connection with the signal arm, whereby if the detector arm should engage the gate member on one side, the gate member will swing freely outward.

33. The combination in a signature gathering or like machine, of grippers normally having a certain definite movement and adapted in said movement to normally convey the signatures or articles from one point to another, and means exercising a control over said grippers whereby to cause the same to deliver the signatures at a point other than the normal point of deposit.

34. The combination in a signature gathering or like machine, of grippers having a movement between two points and adapted normally during such movement to convey the signatures from one point to the other, means exercising a control over the grippers whereby to cause the same to deliver the signatures at a point other than the normal point of deposit, and means arranged to

cause the grippers to resume the normal operation of delivering the signatures to the normal point of deposit.

35. In a signature gathering machine, signature hoppers, a carrier, grippers having a swinging movement between the hoppers and the carrier, actuating means normally causing the grippers to deliver the signatures from the hoppers to the carrier, and means controlling the actuating means under abnormal conditions whereby to cause said actuating means to actuate the grippers to deliver the signatures at a point to one side of the carrier.
36. In a signature gathering machine, the combination with signature hoppers and a carrier, of means acting normally to take the signatures from the hoppers and deposit them on the carrier, and under certain conditions to convey the signatures from the hoppers to another point than the carrier, connections whereby the operation of the

carrier will be interrupted when the signatures are not delivered to the carrier, and means operating automatically to restore 25 the parts to their normal operation.

37. In a signature gathering machine, a gripper having a movement between two extreme points, means actuating the gripper to normally deliver the signatures at a point 30 intermediate the said extreme points, and means controlling said actuating means whereby to cause said actuating means to actuate the gripper to deliver the signatures at the extreme point of travel of said gripper.

Signed at New York city in the county of New York and State of New York this 11th day of January A. D. 1909.

CHARLES A. JUENGST.
